DOLL OR SIMILAR ARTICLE

Virginia Peck Thurman, 179 Howeland Circle,
Danville, Va.

Filed Oct. 9, 1964, Ser. No. 82,107

Term of patent 14 years

(Cl. D34—4)

I claim:

The ornamental design for a doll or similar article, as shown.
